(57) **CLAIM**

The ornamental design for an emesis receptacle, as shown and described.

DESCRIPTION

FIG. 1 is a perspective view of an emesis receptacle;

FIG. 2 is a left side view of the emesis receptacle;

FIG. 3 is a right side view of the emesis receptacle;

FIG. 4 is a front view of the emesis receptacle;

FIG. 5 is a rear view of the emesis receptacle;

FIG. 6 is a top view of the emesis receptacle; and,

FIG. 7 is a bottom view of the emesis receptacle.

The dash type broken lines in the Figures are for the purpose of illustrating unclaimed portions of the emesis receptacle and form no part of the claimed design.
